UNITED STATES PATENT OFFICE.

WILLIAM ZABEL, OF SWISSVALE, PENNSYLVANIA; BERTHA ZABEL, ADMINISTRATRIX OF SAID WILLIAM ZABEL, DECEASED, ASSIGNOR TO THE UNION SWITCH & SIGNAL COMPANY, OF SWISSVALE, PENNSYLVANIA, A CORPORATION OF PENNSYLVANIA.

RESISTANCE UNIT.

1,368,678.

Specification of Letters Patent. Patented Feb. 15, 1921.

Application filed July 15, 1919. Serial No. 311,017.

To all whom it may concern:

Be it known that I, WILLIAM ZABEL, a citizen of the United States, residing at Swissvale, in the county of Allegheny and State of Pennsylvania, have invented certain new and useful Improvements in Resistance Units, of which the following is a specification.

My invention relates to resistance units for use in electrical circuits, and particularly to units which are adjustable to vary the value of the resistance imposed by the unit.

One object of my invention is the provision of a resistance unit which can be manufactured economically, and which embodies adequate support for the resistance conductor with maximum capacity for radiation. A further object of my invention is the provision of a resistance unit having the aforesaid characteristics and also capable of the maximum number of variations in resistance value.

I will describe one form of resistance unit embodying my invention, and will then point out the novel features thereof in claims.

In the accompanying drawings, Figure 1 is a view showing in side elevation, one form of resistance unit embodying my invention. Fig. 2 is a sectional view on a plane indicated by the line II-II in Fig. 1 and looking in the direction of the arrows.

Similar reference characters refer to similar parts in each of the views.

Referring now to the drawings, the reference character 1 designates a base, preferably of insulating material such as porcelain, carrying two spaced terminal posts 2 and 3. Also mounted on the base 1 are two angular brackets 4 and 5, preferably of brass, each having a horizontal portion which is clamped to the base by one of the terminal posts, and a vertical portion which stands upright between the two posts. The upright portions of the two brackets serve as supports for a rotatable drum 6 of insulating material such as bakelite or porcelain. The ends of this drum are provided with two centrally located pivots 7 and 7^a having reduced ends which are journaled in suitable holes in the brackets 4 and 5. These pivots are of suitable electro-conductive material such as brass.

The periphery of the drum 6 is provided

with a plurality of longitudinal recesses 8 which, as here shown, are circular in cross-section. As best illustrated in Fig. 2, these recesses are so located with respect to the surface of the drum that they are nearly closed, there being only a narrow slot along the surface at each recess. The drum is also provided with a circumferential groove 9 midway between its ends, as best shown in Fig. 1, the purpose of which will appear hereinafter.

Mounted in the recesses 8 is a resistance wire 10 which, as here shown, is in the form of a continuous helix. This wire is threaded back and forth through the recesses 8 with successive strands lying in adjacent recesses. The resistance wire 10 is of course substantially inclosed by the recesses near the ends of the drum 6, but each strand is exposed at the middle of the drum because of the circumferential groove 9. Co-acting with these exposed portions of the several strands is a contact finger 11 which is riveted to a brass strip 12, this strip being supported by and in electrical contact with the terminal post 3.

One terminal of the resistance wire is electrically connected with the brass pivot 7 as indicated at 10^a, and so with the bracket 4 and terminal post 2. This connection is preferably effected by placing two washers 13 on the reduced end portion of the pivot 7 and turning the wire end 10^a around the pivot between these washers. The other end of the resistance wire is suitably anchored in the drum 6. It will be evident, therefore, that when the two terminal posts are connected in an electric circuit, the amount of resistance which is interposed in the circuit by the unit may be varied by turning the drum 6 on its axis. The number of adjustments is obviously the same as the number of longitudinal strands of wire, that is, there are two adjustments for each complete loop of wire. It follows that the unit permits of twice as many adjustments as would be possible if the contact finger 11 were mounted for engagement with the wire at one end of the drum or the other. The brackets 4 and 5 are flexible, so that when necessary they can be spread apart far enough to permit the removal of the drum 6 and the insertion of a new drum.

A resistance unit embodying my invention provides adequate support for the re-

sistance wire on the drum, and at the same time it provides for maximum heat radiating capacity. Furthermore, the unit can be manufactured economically.

5 Although I have herein shown and described only one form of resistance unit embodying my invention, it is understood that various changes and modifications may be made therein within the scope of the appended claims without departing from the spirit and scope of my invention.

Having thus described my invention, what I claim is:

1. An adjustable resistance unit comprising a drum mounted to rotate, a continuous resistance conductor threaded back and forth on said drum with the strands parallel to the axis of the drum and with consecutive strands adjacently located, and a contact mounted to engage with said strands.

2. An adjustable resistance unit comprising a drum mounted to rotate, a continuous resistance conductor threaded back and forth on said drum with the strands parallel to the axis of the drum and with the consecutive strands adjacently located, and a contact mounted to engage said strands at a point substantially midway between the ends of the drum.

3. An adjustable resistance unit comprising a drum mounted to rotate and having longitudinal recesses in its periphery, a resistance conductor threaded back and forth in said recesses with consecutive strands lying in adjacent recesses, and a contact mounted to engage said strands at a point substantially midway between the ends of the drum.

4. An adjustable resistance unit comprising a drum mounted to rotate, said drum having a plurality of longitudinal recesses in its periphery and a circumferential groove between the two ends, a resistance conductor threaded back and forth in said longitudinal recesses with consecutive strands lying in adjacent recesses, said conductor being substantially inclosed by the longitudinal recesses except where it intersects said circumferential groove, and a contact mounted to engage the strands of said conductor where they are exposed by the circumferential groove.

5. An adjustable resistance unit comprising a drum mounted to rotate, a continuous helical resistance conductor threaded back and forth on said drum with the strands parallel to the axis of the drum and with consecutive strands adjacently located, and a contact mounted to engage with said strands.

6. A resistance unit comprising a cylindrical member of insulating material having longitudinal recesses in its periphery, and a resistance conductor threaded back and forth in said recess with consecutive strands located in adjacent recesses.

7. A resistance unit comprising a cylindrical member of insulating material having longitudinal recesses in its periphery, and a circumferential groove between its two ends, and a resistance conductor threaded back and forth in said recesses with consecutive strands lying in adjacent recesses, said conductor being substantially inclosed by the longitudinal recesses except where it intersects said circumferential groove.

8. An adjustable resistance unit comprising a supporting block, two terminal posts mounted therein, brackets carried on said block and held in place by said terminal posts, a drum pivoted to rotate in said brackets, a resistance conductor mounted on the periphery of said drum, one terminal of said conductor being electrically connected with one of said terminal posts through one of the brackets, and a contact finger supported by the other terminal post and engaging with said resistance conductor.

9. A resistance unit comprising a supporting block, two spaced brackets mounted on said block, a drum pivoted to rotate in said brackets, and a resistance conductor carried by said drum, said brackets being flexible to permit the removal and insertion of said drum without disturbing the mounting of the brackets.

In testimony whereof I affix my signature in presence of two witnesses.

WILLIAM ZABEL.
